UNITED STATES PATENT OFFICE

95,387

DESIGN FOR A BILLFOLD

William H. St. Thomas, West Bend, Wis., assignor to Amity Leather Products Co., West Bend, Wis., a corporation of Wisconsin

Application February 6, 1935, Serial No. 55,262

Term of patent 7 years

To all whom it may concern:

Be it known that I, William H. St. Thomas, a citizen of the United States, residing in West Bend, in the county of Washington and State of Wisconsin, have invented a new, original, and ornamental Design for a Billfold, of which the following is a specification, reference being had to the accompanying drawing, forming part thereof.

The figure is a perspective view of the billfold.

I claim:

The ornamental design for a billfold, as shown.

WILLIAM H. ST. THOMAS.
